(57) **CLAIM**

We claim the ornamental design for a beverage glass with internal decanting, filtering, mixing and aerating cell, as shown and described.

DESCRIPTION

FIG. 1 is a perspective view of a beverage glass with internal decanting, filtering, mixing and aerating cell showing our new design;

FIG. 2 is a side elevational view thereof;

FIG. 3 is a bottom plan view thereof; and,

FIG. 4 is a top plan view thereof.

The broken lines shown represent unclaimed subject matter and form no part of the claimed design.
